TOILET FLUSH MECHANISM

Leo L. Ingraham, Santa Barbara, Calif.

Application March 11, 1940, Serial No. 323,347

1 Claim. (Cl. 192—142)

This invention relates to toilets and more especially to an improved flush mechanism for the same.

An object of the invention is to provide a simple, practical and efficient mechanism of the 5 character described.

Another object is to provide a noiseless positive acting flush mechanism for toilets.

Another object is to provide a flush mechanism for toilets contained within and forming 10 a part of the toilet seat structure and eliminating the water tank or reservoir.

A further object is to provide a self-contained flush mechanism unit which can be removed and replaced, and one which does not require attachment to a wall structure.

Other objects and advantages will appear and be brought out more fully in the following specification, reference being had to the accompanying drawing, wherein:

Fig. 1 is a perspective view of a toilet embodying my invention;

Fig. 2 is a view showing the mechanical movements involved in the invention;

Fig. 3 is a separate view of the water valve 25 and its actuating gear; and

Fig. 4 is a sectional view taken along the line 4—4 of Fig. 2 illustrating particularly the control cam.

Referring more particularly to the drawing, I show a toilet 5 shown and described more particularly in my copending application filed May 29, 1940, Serial No. 337,882. The toilet comprises a bowl 6 within a casing 7 which is preferably of sound deadening material and separated from the bowl by a space 8. A flush operating mechanism 9 is contained in a space to the rear of bowl 6 within casing 7 which comprises a water supply pipe 10 leading to the interior of bowl 6 in which is positioned a valve 11 having a shaft 12 on which is mounted a gear 13 which engages and is driven by a worm gear 14 mounted on a shaft 15.

A bevel gear 16 is mounted on and drives shaft 15 and engages bevel gears 17 and 18 which are mounted on a shaft 19 but not directly connected to it. Shaft 19 is carried in suitable bearings 20 and is shiftable longitudinally therein under pressure of a spring 21 which bears against the hub of a gear 22 which engages a wide tooth gear 23 mounted on and driven by a shaft 24. A gear 25 mounted on shaft 24 engages a pinion 26 on a motor shaft 27 of a motor 28.

A collar 29 is slidably mounted on shaft 19

and rotates therewith having a slot 30 which engages a pin 31 secured to the shaft. Slot 30 is beveled at one side and forms an abutment for engagement with a dog 32 secured to bevel gear 17. Similarly, a collar 33 is slidably mounted on shaft 19 which rotates therewith having a slot 34 which engages a pin 35 secured to the shaft. Slot 34 is beveled at one side and forms an abutment for engagement with a dog 36 secured to bevel gear 18. A compression spring 37 is positioned on shaft 19 between collars 29 and 33 and tends to keep the collars in separated position.

A gear 38 mounted on shaft 24 drives a gear train 39 which turns a shaft 40 on which is mounted a cam wheel 41 so positioned that a side peripheral portion is opposite the end of shaft 19. This portion of cam wheel 40 is provided with a plurality of cam surfaces against which shaft 19 presses and rides such that as the cam wheel turns shaft 19 is shifted longitudinally so as to provide engagement of dogs 32 or 36 with slot abutments 30 or 34. Cam wheel 41 has a cam surface 42 which, when engaged by the end of shaft 19, causes interengagement of dog 36 and slot abutment 34 resulting in the turning of bevel gear 18 which turns gears 16, 14 and 13 and shaft 12 to open valve 11. Cam wheel 41 has a cam surface 43 and a cam surface 44 which, when the end of shaft 19 is pressed thereagainst, causes the shaft to rotate without the rotation of either gears 17 or 18.

Cam wheel 41 has a cam surface 45 which 35 when the end of shaft 19 is pressed thereagainst is in its extreme position to the left, and dog 32 is engaged by slot abutment 30 and gear 17 turns gear 16 in the opposite direction to which it was turned by gear 18 so as to close valve 11.

An electric switch 46 controls the operation of motor 28 and is provided with a manually actuated plunger 47 which is conveniently located so as to extend exteriorly of the casing 7. A collar 48 is secured to plunger 47 and a bracket 49 is secured so as to secure a spring 50 between it and collar 48. Plunger 47 has a groove 51 in a side portion thereof which is engaged by a spring biased plunger 52 which holds plunger 47 in a downward position until the latter is pushed up by the action of a cam 53 on cam wheel 41.

The operation of the invention should be clear from the foregoing description. At the start of the operation the end of shaft 19 will be pressed against cam surface 44 and both gears

17 and 18 will be disconnected from the shaft. The plunger 47 is depressed, closing switch 46 which starts motor 28 causing shafts 24 and 19 to turn and also cam wheel 41. Cam surface 42 thereupon comes opposite the end of shaft 19 which under the force of spring 21 is caused to shift to the right and dog 36 is engaged by slot abutment 34 causing gears 16, 14 and 13 to turn which opens valve 11 to permit the flow of water from pipe 10 into the toilet bowl. 5

After valve gear 13 has turned substantially a quarter turn, opening valve 11 completely, cam surface 41 comes opposite the end of shaft 19 causing it to be shifted back to the intermediate position and disengaging gear 18. During this period water continues to flow through pipe 10 into the bowl 6 until cam surface 45 comes opposite the end of shaft 19 shifting it to the extreme left position and engaging gear 17 15 which causes a reverse turning of valve gear 13 to close valve 11. At substantially the end of this period cam 53 passes under plunger 47 20

which has been held down by spring plunger 52 forcing it up and disconnecting switch 46 which causes the motor to stop, whereupon the mechanism is in condition for another cycle.

Having described my invention, what I claim is:

Reversible actuating and control means for a rotary shaft as described, comprising a bevel gear on said shaft, a drive shaft therefor adapted to be reciprocated and having a pair of bevel pinion gears mounted thereon engaging said bevel gear, a clutch connection between each of said pinion gears, and said drive shaft adapted to be selectively actuated when said shaft is reciprocated to turn said bevel gear in opposite directions, means to reciprocate said shaft when rotated, a motor drive for said drive shaft and a control switch therefor, said shaft reciprocating means having a cam adapted to disconnect said switch at a predetermined point upon the rotation thereof.

LEO L. INGRAHAM.
